UNITED STATES PATENT OFFICE.

THOMAS M. DANSBY, OF PINE BLUFF, ARKANSAS.

SLICING-MACHINE.

1,153,485.

Specification of Letters Patent. Patented Sept. 14, 1915.

Application filed May 8, 1915. Serial No. 26,860.

To all whom it may concern:

Be it known that I, THOMAS M. DANSBY, a citizen of the United States, residing at Pine Bluff, in the county of Jefferson and 5 State of Arkansas, have invented a new and useful Slicing-Machine, of which the following is a specification.

The present invention appertains to slicing machines, and aims to provide a novel 10 and improved appliance for slicing bacon, ham, and other meats, although it is to be understood that the device may be employed for slicing other articles.

One of the objects of the invention is the 15 provision of a slicing machine having novel means for holding the article to be sliced, and for feeding it to the cutter in a desirable and efficient manner.

Another object of the invention is to provide 20 unique means for adjusting the gage block, whereby slices of various thicknesses can be cut.

A further object of the invention is the 25 provision in a slicing machine, of a novel rind cutter, which will cut off or remove the rind from the slice while the slice is being cut.

A still further object of the invention is to provide a slicing machine having assembled therewith, novel means for sharpening the cutters while the machine is in 30 operation, so that the cutters are kept sharp.

It is also within the scope of the invention to provide a slicing machine having the 35 above named features, and which at the same time, is comparatively simple and inexpensive in construction, as well as being convenient, practical and efficient in use.

With the foregoing and other objects in 40 view which will appear as the description proceeds, the invention resides in the combination and arrangement of parts and in the details of construction hereinafter described and claimed, it being understood 45 that changes in the precise embodiment of the invention herein disclosed can be made within the scope of what is claimed without departing from the spirit of the invention.

The invention is illustrated in the accompanying drawings, wherein:

Figure 1 is a plan view of the improved slicing machine, portions being broken away. Fig. 2 is a side elevation of the machine. Fig. 3 is a longitudinal sectional detail taken on the line 3—3 of Fig. 2, this view being on an enlarged scale. Fig. 4 is a cross section taken on the line 4—4 of

Fig. 1. Fig. 5 is an enlarged sectional detail taken on the line 5—5 of Fig. 1. Fig. 6 is an enlarged fragmental detail of one 60 end portion of the slide.

In carrying out the invention, there is provided a suitable base 1, which is adapted to be set upon a table or other suitable support, and an upstanding guide frame 2 is 65 hinged to one edge of the base, by means of the hinges 3. A slide 4 disposed in a vertical plane is guided for reciprocatory movement within the frame 2 along the above mentioned edge of the base 1, and 70 the outer side of the slide 4 is provided with a handle 5 at the forward end of the slide. This handle 5 enables the slide to be readily actuated manually.

The slide 4 is provided with a triangular 75 opening 6, whose lower edge is disposed adjacent and parallel with the lower edge of the slide 4, and the larger end of the opening 6 is arranged adjacent the rear end of the slide 4. The upper edge of the opening 80 6 is thus inclined rearwardly, and the inner side of the slide 4 is provided with a beveled or inclined seat 7 immediately above the upper edge of the opening 6. The main or slicing cutter or blade 8 rests against the 85 inclined seat 7, and is secured thereto by means of bolts 9 engaging through the cutter and slide. The sharp or active edge of the cutter 8 projects slightly below the upper edge of the opening 6 to properly engage 90 the bacon or other article which is being sliced.

An inclined thumb screw 10 is threaded through a nut 11 embedded within the forward end of the slide 4, the nut 11 being 95 held in place by means of a plate 12 secured to the said end of the slide, and a plunger 13 slides within the bore 14 which receive the screw 10. This bore 14 is drilled in the forward end portion of the slide 4, 100 and extends to the upper edge of the seat 7, whereby when the screw 10 is threaded downwardly, it will force the cutter 8 downwardly. In this manner, when the cutter 8 wears away, it may be fed downwardly, the cutter 8 being provided with 105 slots 8a through which the bolts 9 extend, whereby the cutter may be fed downwardly when the bolts 9 are loosened.

The frame 2 carries an angularly extending guide 15 arranged at right angles relative to the slide 4, and projecting over the base 1. This guide 15 is provided with a series of transverse bottom rollers 16 upon

which the bacon or other article is arranged to rest. A series of upright anti-frictional rollers 17 are carried by the rear side of the guide 15, so as to have one edge of the bacon or article bear thereagainst. The anti-frictional rollers 16 and 17 thus support the bacon or article, whereby the article may be readily fed toward the cutter 8, and will tend to gravitate toward the said cutter, 10 when the guide 15 is inclined. Since the guide 15 is carried by the frame 2, when the frame 2 is swung relative to the base, the guide 15 may be readily inclined, without disturbing the coöperation between the frame 2 and guide 15.

15 A bar or member 18 is disposed above those ends of the rollers 16 remote from the rollers 17, and is carried by the front side of the guide 15. The bar 18 is provided 20 with a pair of outstanding slotted members 19 engaging bolts 20 carried by the forward side of the guide, whereby when the bolts 20 are loosened, the bar 18 may be adjusted to and from the rollers 17, according to the 25 width or size of article. The bar 18 serves to hold the article against the rollers 17.

30 The bottom of the guide 15 is provided with an opening 21, and a block 22 is hinged, as at 23, to the guide 15 adjacent the opening 21, whereby the block 22 may be swung into the opening 20, or under the guide 15. When the block 22 is swung into the opening 21, the guide 15 may swing onto the base 1, whereas if the block 22 is swung under the 35 bottom of the guide, the block 22 will support the guide 15 in an inclined position.

35 A triangular gage board 24 is disposed within the opening 6 of the slide, but is of smaller area than the said opening, the 40 lower edge of the gage board 24 seating slidably upon the lower portion of the slide 4 and the larger end of the board 24 being arranged adjacent the larger end of the opening. A slot is thus provided between 45 the upper edge of the gage board 24 and the sharp or cutting edge of the cutter 8, and the upper edge of the gage board 24 is properly beveled, in order that the slice removed by the cutter 8 will be directed outwardly through said slot.

50 In order to adjustably mount the gage board 24 within the slide 4, the board 24 is provided adjacent its smaller end, with a depending pin or lug 25 which slides in a diagonal slot 26 provided in the lower portion of the slide 4, whereby when the board 24 is reciprocated longitudinally of the slide 4, the smaller end of the board 24 will be shifted transversely of the slide. A plate 55 27 is secured to the outer side of the board 24 adjacent the larger end of the board, and the rear end of the plate 27 is bent angularly or obliquely outward to provide an oblique or diagonal lip 28 which bears 60 against the rear end portion of the slide 4.

65 at the larger end of the opening 6. The slide 4 is provided with an upstanding pin 29 adjacent the larger end of the opening 6, whereby the lip 28 is movable between the pin 29 and larger end of the opening 6, so 70 that the larger end of the board 24 is shifted transversely of the slide 4 when the board 24 is moved longitudinally. The inner side of the board 24 is spaced outwardly slightly from the plane of the inner side of the slide 75 4, whereby when the slide 4 is drawn forwardly to bring the board 24 opposite the guide 15, the bacon or other article in being brought against the board 24, will be projected under the cutter 8. Consequently, by 80 adjusting the board 24 transversely of the slide 4, the thickness of the slice cut by the cutter 8 may be regulated. A coiled wire retractile spring 30 connects the pin 29 and board 24, so as to tend to pull the board 24 85 rearwardly and outwardly.

90 As a means for adjusting the gage board 24, an upright lever 31 has its lower end fulcrumed, as at 32, to the lower portion of the slide 4, at the larger end of the opening 6, and a chain or link element 33 connects the lip 28 and the intermediate portion of the lever 31, whereby when the lever 31 is swung forwardly, the gage board 24 will be moved forwardly. The lever 31 is disposed 95 upon the outer side of the slide 4, and the longitudinal bar 34 disposed upon the outer side of the slide 4 above the opening 6, has its rear end loosely engaged to the upper end of the lever 31. The forward end of the 100 bar 34 is slidable through a staple or keeper 35 carried by the outer side of the slide 4 adjacent the handle 5, and the lower edge of the forward end portion of the bar 34 is provided with a series of notches 36 engageable with the lower portion of the keeper 35. When the forward end of the bar 34 is raised, the notches 36 are disengaged from the lower portion of the keeper 35, and the bar 34 may then be slid longitudinally for 105 adjusting the gage board 24.

110 The rind cutter 37 is slidable transversely through the gage board 24 adjacent the smaller end thereof, and the inner end of the cutter or blade 38 is rounded and sharpened as at 38. The sharpened end 38 of the cutter 37 projects inwardly beyond the inner side of the board 24, and the cutter 37 is arranged adjacent but spaced sufficiently from the lower edge of the gage board 24 115 to properly remove the rind from the slice. The rear edge of the cutter 38 is provided with a series of notches 39, and a latch 40 is pivoted to the outer side of the board 24 in rear of the cutter 38 and has its free end 120 engageable in the notches 39, whereby when the latch 40 is raised or released, the cutter 38 may be adjusted to the desired position, in which event the latch 40 in being swung downwardly will enter the respective notch 125 130

39 for holding the cutter 38 in place properly. The cutter 38 may thus be adjusted in order that its sharp end 39 will project properly beyond the inner side of the gage board.

The sharpening means is carried by the frame 2, and to this end, the frame 2 is provided with an upright opening 41 at the inner side of the slide 4, and a board 42 has its lower end hinged, as at 42^a, to the frame 2 at the lower end of the opening 41. The board 42 is adapted to be swung upwardly into the opening 41 and may be held therein in any suitable manner. An abrasive stone or block 43 is carried by the board 42 to swing or move into the opening 41, when the board 42 is raised. A bolt or equivalent element 44 is engaged slidably through the central portions of the board 42 and stone 43, and the stone 43 is provided with a recess 45 receiving the head of the bolt 44, whereby the bolt 44 will not engage the slide 4 or main cutter 8. A bowed leaf spring 46 has its intermediate portion engaged to the bolt 44 between the stone 43 and board 42, and the ends of the spring 46 bear against the ends of the stone 43 for yieldingly moving the stone 43 away from the board 42 and against the sharp edge of the cutter 8. The abrasive or sharpening stone 43 thus bears against the cutter 8, for sharpening the said cutter when the slide 4 is reciprocated, it being noted that the stone 43 is yieldably supported by the board 42, whereby the stone 43 may yield properly when necessary. The active face of the stone 43 is provided with a transverse slot 47 adjacent the lower end of the stone, through which the sharp end 38 of the rind cutter 39 is movable, and whereby the sharp end of the rind cutter will bear against the walls of the slot 47, when the slide 4 is reciprocated, so that the rind cutter will also be sharpened. The two cutters are thus kept sharp, during the operation of the machine.

A plate 49 is secured to the frame 2 at the end of the guide 15, and has an outstanding sharp tooth or spur 48 which is adapted to engage the respective edge or portion of the article, for preventing the article from lifting or moving upwardly while being sliced. A toothed blade 50 is also preferably carried by the frame 2 at the lower end of the guide 15, and its teeth project slightly upward to assist in holding the bacon or article properly.

From the foregoing, it is believed that the operation and advantages of the present structure will be obvious to those versed in the art, without further comment being necessary.

Having thus described the invention, what is claimed as new is:

1. In a slicing machine, a base, a frame 65 hinged thereto and having an angularly extending guide for an article to be sliced, a slide guided by said frame and having a cutter, the guide having a lower opening, and a block hinged to the guide to swing 70 within the said opening and to swing under the guide for supporting it above the base.

2. In a slicing machine, a reciprocating slide having a slicing cutter, a gage member adjustably carried by the slide, a rind cutter 75 slidable through the gage member, the rind cutter having a series of notches, and a latch pivoted to the gage member and engageable in said notches for holding the rind cutter at various adjusted positions. 80

3. In a slicing machine, a reciprocating slide having a cutter, a gage member carried by the slide, the gage member and slide having interengageable means whereby when the gage member is slid longitudinally it 85 will be shifted transversely, a spring connecting the slide and gage member whereby the gage member is moved in one direction when released, and means for moving and holding the gage member against the action 90 of said spring.

4. In a slicing machine, a frame, a slide guided for reciprocating movement thereby, a slicing cutter and a rind cutter carried by the slide, and a sharpening member carried 95 by the frame and arranged to sharpen both of said cutters.

5. In a slicing machine, a frame, a slide guided for reciprocating movement thereby, a slicing cutter and a rind cutter carried by 100 the slide, and a sharpening member yieldably carried by the frame and bearing against the slicing cutter, the sharpening member having a slot for receiving the rind cutter to sharpen the same. 105

6. In a slicing machine, a frame, a slide guided thereby, a cutter carried by the slide, the frame having an opening at one side of the slide, a member hinged to the frame to swing into said opening, an abrasive member 110 to cooperate with said cutter, an element engaged loosely through said hinged and abrasive members, and a bowed spring engaged to said element and disposed between said hinged and abrasive members for yieldably moving the abrasive member against the cutter. 115

In testimony that I claim the foregoing as my own, I have hereto affixed my signature in the presence of two witnesses.

THOMAS M. DANSBY.
